METALWORKING MACHINE

John J. McGlone, Harvey, and Robert I. Anderson, Chicago, Ill., assignors to Whiting Corporation, Harvey, Ill., a corporation of Illinois

Original application November 21, 1942, Serial No. 466,514. Divided and this application September 3, 1943, Serial No. 501,114

5 Claims. (Cl. 153—28)

The present invention relates generally to machines for working metal in the form of sheets or plates. More particularly the invention relates to that type of metal working machine which serves to carry out or effect an offsetting operation and embodies: (1) a C-shaped housing and supporting structure; (2) a lower shaft which is disposed at the outer extremity or end of the bottom arm of the structure and extends upwardly and outwardly at approximately an angle of 45° with respect to the horizontal, a vertically movable head at the outer end of the top arm of the structure; (3) an upper shaft on the head which extends inwardly and downwardly at substantially a 45° angle and has its inner end disposed normally over and adjacent the outer end of the lower shaft; (4) power driven mechanism including gearing and drive shafts within the structure for conjointly driving the upper and lower shafts in opposite directions; (5) a pair of complementary, coacting offsetting rolls which are mounted on the upper and lower shafts, respectively; and (6) an offsetting gauge attachment which is in the form of a roller equipped bracket, is adapted to gauge or determine the position of the offset or jog with respect to the edges of the work pieces, and is mounted on the bottom arm of the housing and supporting structure so that it may be adjusted to its desired gauging position relatively to the offsetting rolls.

One object of the invention is to provide a metal working machine of this type which is an improvement upon, and has certain advantages over, previously designed machines for the same purpose, and is characterized by the fact that it includes a novel mount whereby the offsetting gauge attachment is supported so that it may be quickly and readily adjusted into any desired gauging position with respect to the offsetting rolls.

Another object of the invention is to provide in connection with a metal working machine of the type under consideration, an offsetting gauge attachment of new and improved form.

Other objects of the invention and the various advantages and characteristics of the present metal working machine will be apparent from a consideration of the following detailed description.

The invention consists in the several novel features which are hereinafter set forth and are more particularly defined by claims at the conclusion hereof.

In the drawings which accompany and form a part of this specification or disclosure and in

which like numerals of reference denote corresponding parts throughout the several views:

Figure 1 is a fragmentary side view of a metal working machine embodying the invention, showing the improved offsetting gauge attachment in place on the novel mount;

Figure 2 is a plan view of the machine, parts being broken away and other parts being shown in section for illustrative purposes;

10 Figure 3 is an enlarged horizontal section taken on the line 3—3 of Figure 1 and showing the offsetting gauge attachment in its operative position on the mount;

15 Figure 4 is an enlarged top or plan view showing in detail the construction and design of the offsetting gauge attachment;

Figure 5 is an enlarged side view of said offsetting gauge attachment;

20 Figure 6 is a vertical transverse section on the line 6—6 of Figure 5; and

Figure 7 is a fragmentary perspective of the front portion of the machine showing in detail the construction and arrangement of the offsetting gauge attachment.

25 The machine which is illustrated in the drawings constitutes the preferred form or embodiment of the invention. It is adapted to carry out or effect offsetting of pieces of sheet or plate metal and includes a pair of complementary coacting offsetting rolls 8 and 9, an offsetting gauge attachment 10, and a mount 11 for the attachment. The offsetting rolls 8 and 9 are adapted, as hereinafter described, to be used with the offsetting gauge attachment 10 to form offsets or jogs in metallic work pieces.

30 The machine, with the exception of the attachment and the mount 11 therefor, is of conventional or standard construction and comprises a C-shaped combined housing and supporting structure 12, a lower roll carrying shaft 13, a vertically movable head 14, an upper roll carrying shaft 15 on the head, and mechanism for conjointly driving the two roll carrying shafts. The combined housing and supporting structure com-

40 prises a hollow bottom arm 16, a hollow top arm 17 and a hollow connecting part 18 and is preferably in the form of a one-piece casting. The bottom arm 16 of the structure has a flat top surface 19 and is so designed or constructed

45 that the bottom portion thereof serves as a base for supporting the machine in an upright position on the floor or foundation of the establishment in which the machine is used. The top arm of the combined housing and supporting structure overlies, and is spaced a substantial

50

distance from, the bottom arm 16 and is connected to the latter by way of the connecting part 18. The lower roll carrying shaft 13 is journaled in a bearing 20 at the outer extremity or end of the bottom arm 16 of the structure 12 and extends upwardly and outwardly at an angle of approximately 45° with respect to the horizontal. The lower end of this shaft is housed within the bottom arm 16 of the structure 12 and the upper end is exposed and is adapted to carry the offsetting roll 8. The head 14 carries the upper shaft 15 and overlies the upper or outer end of the lower shaft 13. It is mounted for vertical sliding movement in a guideway 21 in the outer extremity or end of the top arm 17 and is adapted to be raised or lowered by way of an upstanding screw shaft 22. This screw shaft, as shown in Figure 1, extends through a vertical internally threaded socket in a bracket 23 on the upper portion of the top arm 17 of the structure 12 and has a hand wheel 24 fixed to its upper end. The lower end of the screw shaft is operatively connected to the upper portion of the head 14 so that the screw shaft is rotatable relatively to the head while at the same time the head is connected to the shaft so as to move vertically in connection with such movement of the screw shaft. When the hand wheel 24 is rotated in one direction the head, together with the upper shaft 15, slides downwards towards the outer end of the bottom arm 16 of the structure 12 and when the hand wheel is reversely rotated the head and the upper shaft are caused to slide upwards in a rectilinear course. The upper shaft 15 is journaled in a bearing 25 on the lower portion of the vertically movable head 14 and extends downwardly and inwards at substantially a 45° angle, as shown in Figure 1. The lower or inner end of the upper shaft is adapted to carry the offsetting roll 9. The mechanism for conjointly driving the two shafts 13 and 15 comprises an electric motor 26 on the upper rear corner of the combined housing and supporting structure 12, a horizontally extending drive shaft 27 in the upper rear portion of the structure 12, a horizontally extending driven shaft 28 in parallel relation with the drive shaft 27, change speed gearing 29 between the two last mentioned shafts, a horizontally extending driving shaft 30 in the top arm 17 of the structure 12, a horizontal driving shaft 31 in the bottom arm 14, clutch controlled gearing 32 for driving the drive shaft 30 from the driven shaft 28, a gear train 33 for driving the driving shaft 31 from the driving shaft 30, a pair of meshing bevel gears 34 and 35 between the front end of the driving shaft 30 and the upper outer end of the upper roll carrying shaft 15 for driving the latter shaft from the former shaft, and a pair of meshing bevel gears 36 and 37 between the front end of the driving shaft 31 and the inner end of the roll carrying shaft 13 for driving the latter shaft from said driving shaft 31. The electric motor 26 is drivably connected to the drive shaft 27 by way of a pinion 38 and a gear 39. The change speed gearing 29 between the driving shaft 27 and the driven shaft 28 is in the form of pairs of meshing gears on the two last mentioned shafts and is controlled by a key (not shown) which is slidably mounted in a horizontal keyway 40 in the driven shaft 28 and is adapted, in response to longitudinal adjustment thereof, to lock one of the gears on the driven shaft 28 for drive by the gear on the driving shaft that is in mesh there-

with. Adjustment of the key is effected by way of mechanism including a hand lever 41. The clutch controlled gearing 32 is in the form of a loose pinion 42 on the rear end of the driven shaft 28 and a fixed gear 43 on the rear end of the driving shaft 30. The clutch for controlling such gearing comprises a driving clutch member 44 which is slidably and drivably mounted on the rear extremity of the driven shaft 28 and a driven clutch member 45 which is in opposed relation with the clutch member 44 and is fixed to the pinion 42 of the gearing 32. The clutch member 44 is shifted into and out of engagement with the clutch member 45 by way of mechanism including a hand lever 46 on the front or outer end of the top arm 17 of the combined housing and supporting structure 12. When it is desired to use the machine the hand lever 41 is manipulated so as to bring into operative position the desired pair of gears of the change speed gearing 29. Thereafter the electric motor 26 is started and this results in drive of the driven shaft 28 from the drive shaft 27 through the medium of the change speed gearing 29. After the motor 26 has reached its normal speed the clutch member 44 is shifted into engagement with the clutch member 45 by manipulation of the hand lever 46. Upon engagement of the two clutch members the driving shafts 30 and 31 operate conjointly to drive the roll carrying shafts 15 and 13, respectively. The gearing 32 and the gear train 33 are so designed that the roll carrying shaft 15 is driven in a clockwise direction when viewed from the front of the machine and the lower roll carrying shaft 13 is driven in a counterclockwise direction.

The mount 11 serves as a medium or instrumentality for adjustably supporting the offsetting gauge attachment 10, and consists of a guide rod 47. The latter is located at the so-called feed side of the machine, that is, the side from which the work pieces are fed in connection with an offsetting operation. The rear end of said guide rod 47 is mounted in a horizontal, open-ended socket 49 in a horizontally elongated member 50. The latter has a flat upper portion which underlies, and is connected to, the horizontal leg of an angle bracket 51. The vertical leg of such angle bracket fits against, and is connected to, the connecting part 19 of the combined housing and supporting structure 12. Set screws 52 are disposed in threaded holes in the outer side portion of the member 50 and serve releasably to hold the rear end of the guide rod 47 in the socket 49. The front end of the guide rod 47 fits within a horizontal, open-ended socket 53 in one end of a horizontally elongated bracket 54 and is releasably secured in place by means of a set screw 55 which extends through the outer side portion of said one end of the last mentioned bracket. The central portion of the bracket 54 fits against, and is connected to, the outer or front end of the bottom arm 16 of the structure 12. The guide rod 47 has a flat 56 on the bottom thereof and is normally rigidly held in place by way of the set screws 52 and 55. When the set screws are loosened the guide rod 47 may be removed from the sockets 49 and 53 by sliding it forwards beyond the bracket 54. The socket 53 in the bracket 54 is axially aligned with the socket 49 in the member 50.

The offsetting rolls 8 and 9 are removably mounted on their respective shafts 15 and 13 in order that different types of rolls, such for example as flanging rolls or slitting rolls, may be

substituted therefor when it is desired to use the machine to effect different types of metal working operations. The periphery of the roll 8 has a 45° taper in the direction of the inner lower end of the shaft 15. The roll 9 is of composite character and comprises an outer part 9a and an inner part 9b. The peripheries of these two parts have a 45° taper, as shown in Figure 5. The plane of the periphery of the inner part 9b is inset with respect to the plane of the periphery of the outer part 9a of the roll 9 with the result that there is a step 9c between the two parts. When the two offsetting rolls 8 and 9 are mounted on the shafts 15 and 13, respectively, and the two shafts are properly adjusted, one relatively to the other, the roll 8 is disposed over the inner part 9b of the roll 9 directly inwards of the step 9c and the two rolls are so arranged that during drive thereof they coact to effect an offset or jog in any work piece that is fed between them from the feed side of the machine to the discharge side.

The offsetting gauge attachment 11 serves as a means for gauging or determining the position of the offset or jog with respect to the edges of the work pieces that are fed between the rolls 8 and 9. It is mounted removably on the guide rod 47 of the mount 11 and comprises a two piece cast metal bracket 57 and a roller 58. The bracket consists of a vertically elongated upper piece 59 and a bottom piece 60. The lower end of the upper piece has a downwardly facing groove 61 of semi-circular cross section for receiving the top portion of the guide rod 47. The bottom piece 60 of the bracket 57 is removably connected to the lower end of the upper piece 59 by bolts 60a and has an upwardly facing groove 62 of semi-circular cross section for receiving the bottom portion of the guide rod 47. The two grooves 61 and 62 define a cylindrical socket which permits the offsetting gauge attachment 10 to be slid longitudinally of the guide rod 47. Two set screws 63 extend through threaded holes in the central portion of the bottom piece 60 of the bracket 57 and serve, when tightened, to lock the bracket against displacement relatively to the guide rod 47. The upper or inner ends of these two set screws are adapted to engage the flat 56 on the bottom portion of the guide rod 47, as shown in Figure 6 of the drawings. The upper end of the upper piece 59 of the bracket is in the form of a pair of right angle webs, one of which is on the inside of the bracket and extends lengthwise of the bottom arm 16 of the combined housing and supporting structure 12 and the other of which is joined to, and projects outwardly from, the front margin of the one web and extends at right angles to the guide rod 47. The inner web is provided with a pair of vertically spaced, inwardly extending, integral ears 64 and these have vertically aligned circular holes 65. The roller 58 of the attachment 10 has a cylindrical outer periphery and is disposed between the ears 64. It is confined against vertical displacement by the ears and is rotatably mounted on a vertically extending cylindrical pin 66. The ends of the pin fit within the holes 65 in the ears 64 and are locked in place by way of set screws or any other suitable means. The roller 58 is free to rotate about the pin 66 and serves as a stop or guide for the inner edges of the work pieces that are fed between the complementary coacting offsetting rolls 8 and 9 (see Figures 4 and 5). The position of the roller 58 with respect to the offsetting rolls gauges or determines the distance of the offsets or

jogs from the inner edges of the work pieces. By adjusting the attachment 10 rearwards on the guide rod 47 the offsets or jogs are inset an appreciable distance from the inner edges of the work pieces whereas forward adjustment of the attachment 10 on the guide rod 47 results in the offsets or jogs being inset but a small distance from the inner edges of the work pieces. When it is desired to adjust the attachment 10 the set screws 63 are released and the roller equipped bracket is shifted or slid to the desired position. Thereafter the set screws 63 are tightened so as to lock or fix the attachment 10 in place. The bracket 57 is so designed that the roller 58 projects above and below the operative portions of the offsetting rolls 8 and 9. When the attachment is in its operative position the roller 58 is located on the feed side of the machine but in close proximity to the two offsetting rolls. In order to hold the attachment in an upright position and against tilting in the direction of the bottom arm 16 of the combined housing and supporting structure 12 a vertically extending cap screw 67 is provided. This screw extends through an inwardly extending lug 68 on the lowermost ear 64 and is adapted to engage and slide on the flat upper surface of the lower arm 16 of the structure 12. In connection with use of the offsetting rolls 8 and 9 and the offsetting gauge attachment 10 a horizontal hold-down roller 69 is generally employed. This roller, as shown in Figure 5, is located outwards of the two offsetting rolls and is carried by a bracket 70 which is removably secured to the vertically movable head 14.

When it is desired to provide offsets or jogs in sheet or plate metal work pieces the attachment 10 is adjusted or manipulated to the desired position on the guide rod 47 and the machine is then started by connecting the two offsetting rolls for drive by the electric motor 26. Thereafter the work pieces are successively fed past the roller 58 of the attachment 10 and between the two offsetting rolls 8 and 9. During passage of the pieces past the two rolls the latter, in conjunction with the hold-down roller 69, form the desired offsets or jogs in the pieces. The offsetting gauge attachment 10 may be removed either by withdrawing the bolts 60a for clamping together the upper and bottom pieces of the bracket 57 or by loosening the set screws 63 and then sliding the guide rod 47 forwards so as to permit the bracket to be slid rearwards out of engagement therewith. But a single attachment 10 need be employed for the reason that in connection with an offsetting operation the direction of rotation of the offsetting rolls is such that the work piece tends to swing in the direction of the roller 58.

The herein described metal working machine 60 is highly efficient in operation due to the specific design and arrangement of the offsetting gauge attachment 10 and its mount 11. The mount permits of ready adjustment and removal of the attachment. The attachment is simple in construction and hence may be produced at a low cost.

The invention is not to be understood as restricted to the details set forth since these may be modified within the scope of the appended claims without departing from the spirit and scope of the invention.

This application is a division of an application filed by us on November 21, 1942, Serial 466,514.

Having thus described the invention what we

claim as new and desire to secure by Letters Patent is:

1. In a metal working machine of the character described, the combination with a C-shaped supporting structure, a pair of shafts mounted one at the outer end of the bottom arm of the structure and the other at the outer end of the top arm of said structure, and having certain ends thereof disposed adjacent one another and provided with complementary coacting offsetting rolls, and power driven mechanism for conjointly driving the shafts in opposite directions, of a horizontal guide rod mounted on the structure and positioned outwards of and along one side of said bottom arm of the structure, and an offsetting gauge attachment comprising an upstanding bracket having at the lower end thereof an open-ended socket in surrounding and slidable relation with the guide rod and provided at its upper end with a pair of vertically spaced laterally and inwardly extending integral ears, a vertical pin having the ends thereof mounted in the ears, and a cylindrical roller mounted on the intermediate portion of the pin and adapted to engage certain edges of the work pieces in connection with the feed of such pieces between the offsetting rolls.

2. In a metal working machine of the character described, the combination with a C-shaped supporting structure, a pair of shafts mounted one at the outer end of the bottom arm of the structure the other at the outer end of the top arm of said structure, and having certain ends thereof disposed adjacent one another and provided with complementary coacting offsetting rolls, and power driven mechanism for conjointly driving the shafts in opposite directions, of a cylindrical horizontal guide rod mounted on the structure and positioned outwards of and along one side of said bottom arm, and an adjustable offsetting gauge attachment comprising a vertically elongated bracket having at its lower end a cylindrical open-ended socket for slidably receiving the guide rod, and at its upper end an inwardly disposed element for engaging certain edges of the work pieces in connection with feed of such pieces between the offsetting rolls, and provided at the inner side thereof with a vertically extending screw adapted to engage the top surface of said bottom arm of the structure and also adjustably to limit inward swinging of the bracket relatively to the guide rod.

3. In a metal working machine of the character described, the combination with a C-shaped supporting structure, a pair of shafts mounted one at the outer end of the bottom arm of the structure and the other for vertical adjustment at the outer end of the top arm of said structure, and having certain ends thereof disposed adjacent one another and provided with complementary coacting offsetting rolls, and power driven mechanism for conjointly driving the shafts in opposite directions, of a cylindrical horizontal guide rod mounted on the structure so that it extends outwards of, and along one

side of, the bottom arm of the structure, and an adjustable offsetting gauge attachment comprising a vertically elongated bracket having at its lower end a cylindrical open-ended socket for slidably receiving the guide rod and at its upper end a vertical roller for engaging certain edges of the work pieces in connection with feed of such pieces between the offsetting rolls, and provided at the inner side thereof with a vertically extending screw adapted to engage the top surface of said bottom arm and also adjustably to limit inward swinging of the bracket relatively to the guide rod.

4. In a metal working machine of the character described, the combination with a C-shaped supporting structure, a pair of shafts mounted one at the outer end of the bottom arm of the structure and the other for vertical adjustment at the outer end of the top arm of said structure, and having certain ends thereof disposed adjacent one another and provided with complementary coacting offsetting rolls, and power driven mechanism for conjointly driving the shafts in opposite directions, of a cylindrical horizontal guide rod mounted on the structure so that it extends outwards of, and along one side of, the bottom arm of the structure, and an adjustable offsetting gauge attachment comprising a vertically elongated bracket having at its lower end a cylindrical open-ended socket for slidably receiving the guide rod and at its upper end a pair of vertically spaced laterally and inwardly extending ears, together with a vertical roller disposed between the ears and adapted to engage certain edges of the work pieces in connection with feed of such pieces between the offsetting rolls, and a vertically extending screw carried by the lower-most ear and adapted to engage the top surface of said bottom arm and also adjustable to limit inward swinging of the bracket relatively to the guide rod.

5. In a metal working machine of the character described, the combination with a C-shaped supporting structure, a pair of shafts mounted one at the outer end of the bottom arm of the structure and the other at the outer end of the top arm of said structure, and having certain ends thereof disposed adjacent one another and provided with complementary coacting offsetting rolls, and power driven mechanism for conjointly driving the shafts in opposite directions, of a horizontal guide rod mounted on the structure and positioned outwards of and along one side of said bottom arm of the structure, and an adjustable offsetting gauge attachment comprising an upstanding bracket having at the lower end thereof a split bearing for removably and adjustably connecting the bracket to said guide rod, and provided at its upper inner portion with a laterally offset vertical roller for engaging certain edges of the work pieces in connection with the feed of such pieces between the offsetting rolls.
